PAPER MOP

Alfred C. Stepan, Brenham, Tex.

Application September 17, 1936, Serial No. 101,313

2 Claims. (Cl. 15—225)

This invention relates to a mop and it aims to provide a novel construction providing a plurality of mopping portions, which is inexpensive.

It is further aimed to provide such a construction which is manufactured from paper, which has better cleansing qualities than other materials, and which may nevertheless be used for all purposes for which cloth is at present employed.

10 It is further aimed to provide such a construction consisting of a roll of paper perforated at various elevations to enable detachment of the lowermost portion when used, the construction preferably employing a cover for protecting and 15 stabilizing purposes and the uppermost portion of the mop also preferably being surrounded by a reenforcing cord or the like, and the cover being separable in sections.

The more specific objects and advantages will 20 become apparent from a consideration of the description following taken in connection with accompanying drawing illustrating an operative embodiment.

In said drawing:—

25 Figure 1 is a side elevation of the mop, with the cover in place;

Figure 2 is a view in side elevation, partly broken away, with the cover shown in central vertical section;

30 Figure 3 is a horizontal sectional view taken on the line 3—3 of Figure 1, and

Figure 4 is a detail elevation of a fragment of the sheet from which the mop is made.

Referring specifically to the drawing, the mop 35 body consists of a tightly rolled sheet of paper 10 the same being of any desired dimensions as to the roll and the paper sheet being of any preferred thickness, the thicknesses varying according to the different purposes for which the mop 40 is used. It will be noted that the sheet 10 has lines of perforations or is otherwise weakened or scored as at 11. The lower end of the mop or cylinder formed by the roll of paper is the one used for mopping purposes, being engaged 45 with the floor or any other surface at the lower end of the roll. When such lower end portion is used or is no longer effective, it is severed or removed by tearing the same along the lowermost row of perforations 11, thereby producing 50 a new lower end surface constituting a mopping surface. Such action of removing the lowermost portion after use or it becomes ineffective, is repeated by successively removing the lowermost

portion along the lines of perforations. It will be noted that the uppermost portion of the roll, that is above the upper row of perforations 11, is tightened and reenforced by a band 12, for instance a cord of textile material, tied as at 13. 5

The mop is reenforced and protected by a cover or cap 14 preferably made of strong paper and having a cylindrical wall 15 telescoped over the mop body and closed at the top as by means of an end wall 16. Such cover terminates at the 10 lowermost row of perforations so as to leave an effective mopping portion exposed. The cover is also perforated, weakened or scored as at 16^a and each time the lowermost portion of the mop body is torn or removed from the remainder, the 15 lowermost portion of the cover 15 is torn or removed at the lowermost row of perforations 16^a, thereby leaving an exposed mopping portion.

Various changes may be resorted to provided they fall within the spirit and scope of the invention. 20

I claim as my invention:—

1. A mop of the class described comprising a roll of elongated sheet material rolled in the direction of its greatest length, said sheet material 25 having lines of perforations longitudinally thereof whereby they will be arranged at different heights in the mop, to permit removal of cylindrical portions of the mop as they become ineffective, and means on the rolled sheet above the 30 uppermost perforations operating to maintain the sheet in rolled form, said sheet being of paper, and a cylindrical cover about the mop, said cover being in separable portions to enable its gradual removal corresponding to the removal of 35 portions of the mop.

2. A mop of the class described comprising a cylinder of elongated sheet material rolled in the direction of its greatest length into relatively compact form and adapted to be used on end, 40 said cylinder being divided into a plurality of cylindrical portions by lines of perforations made longitudinally of the material and parallel with each other and aligned in the cylinder, said portions being adapted for separation at the perforations to present a fresh surface for use, and a cylindrical cover about the cylinder provided with separable sections formed by rows of perforations aligned with the perforations in the cylinder for removal of a section of the cover 45 with the removal of each portion of the cylinder. 50

ALFRED C. STEPAN.
